UNITED STATES PATENT OFFICE

NOBLE H. WATTS, OF BRIDGEPORT, CONNECTICUT, ASSIGNOR TO GENERAL ELECTRIC COMPANY, A CORPORATION OF NEW YORK

DESIGN FOR AN IRONER

Application filed March 9, 1932. Serial No. 43,140. Term of patent 14 years

To all whom it may concern:

Be it known that I, NOBLE H. WATTS, a citizen of the United States, residing at Bridgeport, in the county of Fairfield, State of Connecticut, have invented a new, original, and ornamental Design for an Ironer of which the following is a specification, reference being had to the accompanying drawing, forming a part thereof.

In the drawing, Fig. 1 is a perspective view of an ironer, showing my new design and Fig. 2 is a side elevation of the ironer.

I claim:

The ornamental design for an ironer as shown.

In witness whereof, I have hereunto set my hand.

NOBLE H. WATTS.
